ASH TRAY

John D. Goodell, St. Paul, Minn., assignor to Brown & Bigelow, St. Paul, Minn.

Application July 26, 1957, Serial No. 47,094

Term of patent 3½ years

(Cl. D85—2)

FIG. 1

FIG. 2

Fig. 1 is a top plan view of an ash tray showing my new design; and

Fig. 2 is a perspective view thereof.

The characteristic features of my design reside in the centrally located cigarette supporting element.

I claim:

The ornamental design for an ash tray, as shown and described.
